UNITED STATES PATENT OFFICE.

JACOB T. UDEN, OF NEW YORK, N. Y.

SAWING APPARATUS.

Application filed August 25, 1922. Serial No. 584,282.

To all whom it may concern:

Be it known that I, JACOB T. UDEN, a citizen of Russia, and resident of New York city, in the county of New York and State 5 of New York, have invented certain new and useful Improvements in Sawing Apparatus, of which the following is a specification.

My invention relates to sawing apparatus 10 and has a particular reference to apparatus employing a movable straight saw blade in a stationary frame.

The object of my invention is to provide a portable sawing apparatus adapted to be 15 attached to the work, such as a log, standing tree etc., and further adapted to be operated by a single person.

My invention is more fully described in the accompanying specification and drawing in which—

Fig. 1 is an elevation of my apparatus, Fig. 2 is a rear view, Fig. 3 is a partial plan view, and Fig. 4 is a sectional view of a portion of my apparatus.

My sawing apparatus consists of a frame 1 formed of two flat pieces 1' and 1'', joined together by means of bolts or rivets 2 and spacers 3. The ends of the frame are provided with guiding plates 4 for sliding 25 blocks 5 to which the ends of a saw blade 6 are attached. The other ends of the blocks 5 have holes 7 for the ends of a chain or steel cable 8 (or any other suitable flexible carrier). This cable is stretched around the 30 frame 1 on rollers 9 and is attached to a rotating sleeve 10 on a crank 11. The ends of this crank are rotatively mounted in the frame, and a pinion 12 is attached to one end of this crank. This pinion meshes with 35 a gear 13 with a handle 14 for a manual operation. Instead of this handle a pulley for 40 a motor drive may be attached.

The rotation of the crank 11 will cause the cable to move back and forth, and with 45 it will reciprocate the saw blade 6. The cable may be tightened by means of a screw 15 engaging blocks 16 for the ends of a shaft 17 of the roller 9, these blocks being placed in slots 18.

The tightness of the cable varies with each 50 revolution of the crank, and in order to maintain it under a tension, I attach a shaft 19 with rollers 20 to the cable, and provide cam surfaces on the frame for these 55 rollers. These cam surfaces comprise a depression 22 occupied by the rollers 19, when

the crank 11 is at right angle with a line C—C which is tangent to the wheels 9, and elevated portions 21 occupied by the rollers when crank 11 is in one of the dead centers. 60 Lines L—L indicate the extreme positions of the rollers. The curve or cam surface 21—22 is so shaped, that the cable tension remains practically constant for all positions of the crank 11. These surfaces are 65 so spaced, that with the crank 11 in one dead center the rollers engage the high point 22, thereby keeping the cable tight, and with the crank at right angles with the cable the 70 rollers slide into depressions 21.

The frame 1 is provided with apertures 23 for a shaft 24 with a ratchet wheel 25. The shaft is attached to a sliding box 26 with rollers 27. The end of the shaft 24 has a slot 28 for a spring catch or pawl 29 on 75 the frame 1.

The sliding box 26 is mounted on a stand 30 and may be moved up or down by means of a cable or chain 31, stretched around rollers 32 on the stand. A handle 32' may 80 be used for operating the cable. The cable ends are attached to the box 26.

The frame may be quickly removed from the stand by depressing the catch 29 and 85 sliding it off the shaft 24.

When in operation the saw may be placed in any angular position by locking the frame 1 on the ratchet wheel 25 by means of a pawl 33.

With the arrangement shown the weight 90 of the frame 1 will keep the saw pressed against the work, such as a log 34. A spring 35 may be also used, the position and tension of the spring being adjusted by placing the pin 36 in different holes 37 in the stand 95 30. This spring is especially useful, when the saw is used for sawing off trees with the stand 30 in a horizontal position.

The stand 30 has an extension lug 38 with 100 tongues 39 and 40, forming a clamp for the work, such as a log 34. The other ends of the tongues are drawn together by means of a chain 42, attached with one end to the tongue 40 and wound around a sprocket 41 on the tongue 39. The sprocket has a handle 43. A pawl 44 locks the sprocket, when 105 the chain is tightened.

Important advantages of my sawing apparatus are, that it can be operated by one person, can be easily moved from one place 110 to the other, can be attached to the work, and can be adjusted for various degrees of

pressure required between the saw and the work.

I claim as my invention:

1. In a sawing apparatus, the combination with an open frame, a saw blade placed between the ends of said frame, holders for the ends of said blade slidably mounted in the ends of said frame, a flexible carrier attached to the ends of said frame, a plurality of rollers supporting said flexible carrier, a crank shaft adapted to impart a reciprocating movement to said flexible carrier, and rollers attached to said flexible carrier and adapted to slide over said frame, the frame under said rollers being cam shaped so as to keep said flexible carrier under tension for all positions of said crank shaft.
2. In a sawing apparatus, the combination with an open frame, a saw blade placed between the ends of said frame, holders for

the ends of said saw blade slidably mounted in said frame, a flexible carrier attached to said holders, a plurality of rollers around said frame adapted to support said flexible carrier, a crank rotatively mounted in said frame, said flexible carrier being attached to said crank so as to receive a reciprocating movement when said crank is rotated, and a pair of rollers attached to said flexible carrier and adapted to slide over the edges of said frame, said edges being cam shaped and comprising elevations for said pair of rollers, when said crank is in one of the dead centers, and a depression when said crank is at right angle to a line tangent to said rollers supporting said flexible carrier.

Signed at New York in the county of New York and State of New York this 12 day of August A. D. 1922.

JACOB T. UDEN.
